SANDAL OR SIMILAR ARTICLE

Samu-El Ish-Shalom, New York, N. Y.

Application August 18, 1950, Serial No. 11,831

Term of patent 14 years

(Cl. D7—7)

To all whom it may concern:

Be it known that I, Samu-El Ish-Shalom, a citizen of the United States, residing at 11-A Clinton Street, New York, N. Y., have invented a new, original, and ornamental Design for a Sandal or Similar Article, of which the following is a specification, reference being had to the accompanying drawing, forming a part hereof.

Figure 1 is a side elevational view of a sandal showing my new design, the broken lines being for illustrative purposes only; and

I claim:

The ornamental design for a sandal or similar article, as shown and described.

SAMU-EL ISH-SHALOM.
